UNITED STATES PATENT OFFICE.

EMIL A. MILLER, OF OAKLAND, CALIFORNIA, ASSIGNOR OF ONE-HALF TO CHARLES L. KOERNER, OF OAKLAND, CALIFORNIA.

ROTARY ENGINE.

1,343,331.

Specification of Letters Patent. Patented June 15, 1920.

Application filed January 13, 1919. Serial No. 270,964.

To all whom it may concern:

Be it known that I, EMIL A. MILLER, citizen of the United States, residing at Oakland, in the county of Alameda and State of California, have invented certain new and useful Improvements in Rotary Engines, of which the following is a specification.

This invention relates to rotary engines of the type in which the cylinder rotates about a fixed axis and the end of the piston rods act against inclined surfaces.

The principal object of my invention is to provide an improved engine of the above mentioned type which is simple in construction and reliable in operation and in which each cylinder performs more than a single cycle for each revolution of the engine shaft.

Another object is to provide improved means for operating the engine valves and in connection therewith to provide means by which the engine may be easily reversed.

With these and other objects in view the invention consists in certain novel features of construction, combination and arrangements of parts which are hereinafter more specifically described and pointed out in the appended claims.

Referring to the drawings forming a part of the specification:

Figure 1 is a view in front elevation of my improved engine.

Fig. 2 is a view in vertical section through the same.

Fig. 3 is a view in section on the line 3-3

Fig. 2.

Referring to corresponding parts in the several views by the same numerals of reference; 1 denotes a base plate from which extends a pillar 2 the upper end 3 of which is cylindrical and provides a journal 4 for the rotating shaft of the engine.

Formed on this pillar or attached thereto is a concave frame 5 the outer edge of which has an inwardly extending flange 6 to which is bolted the curb plate 7. The latter lies in a plane at right angles to the axis of rotation of the engine. Plate 1 has an opening through which the frame 5 extends and at the lower part of the latter is a segmental wall 8. A plate forming a corresponding wall 9 is attached to the front edge of the frame 5, these two walls forming a cavity 10 into which dip the outer ends of the piston rods.

Revolutely mounted in journal 4 is the 55 main bearing shaft 12 which on the end within frame 5 is provided with a radially extending flange 13. The cylinders are denoted in general by 14 and are provided with lugs 15 by which they are bolted to the 60 face of flange 13. Each cylinder is provided with an intake port 16 and an exhaust port 17. This latter port alines with a transverse passage 20 extending through flange 13.

On that part of head 3 which extends 65 through frame 5 there is formed a cavity 18 having an annular opening 19 around the entire front end of the head. This opening is arranged so that the passageways 20 communicate therewith and the front end of 70 the hub and rear face of flange 13 are finished to make a reasonably close joint. To cavity 18 is attached pipe 21 by which the exhaust gases are conveyed away from the immediate vicinity of the engine. 75

The intake and exhaust are controlled by valves 21 and 22 respectively and these valves are operated by the rock-arm 23 and 24 which are pivotally mounted in ears 25. One end of each of these levers contacts with the 80 stem of the respective valve while the opposite ends have rollers 27 for contact with operating cams.

Attached to base 1 on the opposite side of the frame 5 is a stand 30 having an opening 85 therethrough the axis of which is in alignment with the axis of shaft 12. Held in this opening is the hub 31 of a plate 32. This hub does not rotate but on the contrary is held against rotation as by the lock nut 33. 90

On the outer circumference of the plate 32 is a toothed gear 34 and inside of the latter is a toothed gear 35. One of these gears is made oscillative with respect to the other, as here shown gear 35 is revolute on the 95 wedge shaped ring 36. By tightening this ring toward the plate 32 the gear will be held rigid while if the ring is slackened off the gear may be turned.

Revolutely mounted in hub 31 is a tubular 100 shaft 40 the inner end of which is provided with arms 41. Passageways 42 extend through these arms and terminate in openings 43 which aline with the intake ports 16. Suitable means are provided for attaching the ends of the arms to the side of the cylinder and each arm is provided with lugs 44 for the reception of the pins 45 and

46. Revolubly mounted on pin 46 is a rigidly connected cam 47 and gear 48 the latter meshing with gear 35.

5 In like manner a rigidly connected cam 49 and gear 50 are revoluble on the pin 45 and this gear meshes with gear 34. Cams 47 and 49 through the contacting rollers 27 move the rock-arms 23 and 24.

10 The cylinders 14 are arranged in diametrically disposed pairs and the pistons 51 of each pair are connected by a rod 52 which extends through stuffing-box 53 in the cylinder heads. To enable the rods of different pairs to cross each other I set the various 15 pairs at different distances from the flange 13 and correspondingly change the length of the rock-arms, while the ends of those rods which are nearest the flange have an offset bend to bring their ends into alinement with 20 plate 7. Rods 52 extend through the pistons and have their outer ends forked to receive rollers 54. The latter contact with the inner surface of the ring which is provided with a series of inclined abutments 55.

25 Extending outwardly from the cylinders 14 are guide-arms 56 which contact with the side faces of the ring 7. These arms are provided with slots or grooves 57 and the pins 58 on which rollers 54 are mounted extend into these slots.

30 The ratio of the fixed to the rotatable gears 48 and 50 is such that the valves are operated in proper relation to the inclines 55, thus if the engine was operating as a four 35 cycle gas engine and five abutments were used, this ratio would be $2\frac{1}{2}$ to 1.

35 In operation the gaseous fuel, steam, or compressed air which enters through the passageway 60, is admitted through valve 21 40 above the piston. Expansion therein takes place driving the rod 52 outwardly in respect to that cylinder. This outward pressure of the piston-rod causes its roller to exert a force against one of the inclined abutments, 45 which is resoluble into two components, one of which causes the cylinders to rotate with respect to the plate 7. The side pressure which is exerted on the roller is taken care of by the pin 58 working in the guide slot 57.

50 The rotation of the cylinders carries with it the gears 48 and 50, together with their attached cams. These cams move the rock-arms 23 and 24 and thus at the proper time open the intake and exhaust valves.

55 If the engine is to operate in a reverse direction then gear 35 is turned so that the cams which operate the intake valves will bear an opposite time relation to the cams operating the exhaust valves and so the cylinder will operate in like manner.

60 The exhaust passes out through port 17, the holes 20 and discharges through the annular opening 19 into chamber 18.

65 Thus I have provided an engine operable by various gaseous media which is compara-

tively simple in construction and design and while I have shown the preferred embodiment of my invention, it will be understood that changes may be made within the scope of the claims without departing from the 70 spirit of the invention or sacrificing any of the advantages thereof.

I claim as new and wish to cover by Letters Patent:—

1. An engine of the character described 75 comprising a revoluble shaft, a plurality of cylinders attached to said shaft in diametrically disposed pairs, pistons in said cylinders, rods having said pistons connected thereon, a ring having a plurality of inclined abutments lying in the plane of rotation of said cylinders, and rollers carried by the ends of said rod for contact with said abutments.

2. An engine of the character described 85 comprising a plurality of pairs of diametrically disposed cylinders, pistons reciprocable in said cylinders, rods extending through the pistons of oppositely disposed cylinders and attached thereto, a curb plate 90 disposed in the plane of said cylinders, and abutments carried by said plate against which outer ends of said rods are adapted to contact.

3. An engine of the character described 95 comprising a plurality of pairs of diametrically disposed cylinders, pistons reciprocable in said cylinders, rods extending through the pistons of oppositely disposed cylinders and attached thereto, a curb plate 100 disposed in the plane of said cylinders and abutments carried by said plate for contact with the ends of said rod, said cylinders having intake and exhaust ports, valves controlling said ports, and means for operating 105 said valves.

4. An engine of the character described comprising a plurality of pairs of diametrically disposed cylinders, pistons reciprocable in said cylinders, rods extending through the 110 pistons of oppositely disposed cylinders and attached thereto, a curb plate disposed in the plane of said cylinders, abutments carried by said plate for contact with the ends of said rod, said cylinders having intake and exhaust ports, valves controlling said ports, cam means for operating said valves and gear means for operating said cams.

5. An engine of the character described comprising a plurality of pairs of diametrically disposed cylinders, pistons reciprocable in said cylinders, rods extending through the pistons of oppositely disposed cylinders and attached thereto, a curb plate disposed in the plane of said cylinders, inclined abutments carried by said plate for contact with the ends of said rod, said cylinders having intake and exhaust ports, valves controlling said ports, cam means for operating said valves, gears revoluble with said cams, the 120

125

130

axes of said cams and gears being in fixed relation to said cylinders and co-meshing gears for driving said cam operating gears.

6. An engine of the character described comprising a plurality of pairs of diametrically disposed cylinders, pistons reciprocable in said cylinders, rods extending through the pistons of oppositely disposed cylinders and attached thereto, a curb plate disposed in the plane of said cylinders, inclined abutments carried by said plate for contact with the ends of said rod, said cylinders having intake and exhaust ports, valves controlling said ports, pivotally mounted rock-arms for operating said valves, cams for moving said rock-arms, toothed gears revoluble with said cams, said cams and gears being revoluble with said cylinders, and non-rotating co-meshing toothed gears for driving said cam operating gears.

7. An engine of the character described comprising a plurality of pairs of diametrically disposed revolubly mounted cylinders, pistons reciprocable in said cylinders, rods extending through the pistons of oppositely disposed cylinders and attached thereto, a non-revoluble curb plate disposed in the plane of said cylinders, abutments carried by said plate against which the outer ends of said rods are adapted to contact, guides carried by said cylinders adapted to embrace said curb plate, said cylinders having intake and exhaust ports, valves controlling the intake and exhaust ports of said engine, pivotally mounted rock-arms for operating said valves, cams for moving said rock-arms, toothed gears revoluble with said cams, said cams and gears being

revoluble with said cylinders, and non-rotating co-meshing toothed gears for driving said cam operating gears.

8. An engine of the character described comprising a revolubly mounted shaft a plurality of diametrically disposed pairs of cylinders having their longitudinal center lines in radial relation and planes perpendicular to the axis of rotation of said shaft and revoluble therewith, pistons in said cylinders, rods rigidly connecting the pistons of each pair, piston rods extending outwardly from said pistons, contact rollers carried by the outer ends thereof, a stationary curb plate lying in the plane of rotation of said cylinders, a plurality of inclined abutments carried by said plate, and guides carried by said cylinder adapted to embrace said plate.

9. An engine of the character described comprising a revolubly mounted shaft a plurality of diametrically disposed pairs of cylinders having their longitudinal center lines in radial relation and planes perpendicular to the axis of rotation of said shaft and revoluble therewith, said cylinder having exhaust and intake ports, valves controlling said ports, rock-arms for operating said cylinders for operating said rock-arms, toothed gears revoluble with said cams, non-revolubly mounted gears for coöperation with said cam gears and means to permit a limited oscillative movement of one of said non-revoluble gears for the purpose of varying the time relation between the exhaust cams and the intake cams.

In testimony whereof I affix my signature.

EMIL A. MILLER.
